UNITED STATES PATENT OFFICE.

MOSES E. BLOOM, OF NEW YORK, N. Y.

POISON-TABLET.

1,156,584.

Specification of Letters Patent. Patented Oct. 12, 1915.

Application filed December 29, 1913. Serial No. 809,172.

To all whom it may concern:

Be it known that I, MOSES E. BLOOM, a citizen of the United States, and a resident of New York, in the county of New York and State of New York, have invented certain new and useful Improvements in Poison-Tablets, of which the following is a specification.

My invention relates to poison-tablets and 10 has for its object the production of a tablet of simple construction, of low cost to manufacture and designed primarily to render an accidental internal taking thereof impossible or an intentional internal taking of the poison 15 very difficult.

Means for preventing the accidental swallowing of poisons in tablet form, such as bichlorid of mercury, have long been sought, and my invention contemplates the interlocking of the poisonous preparation with a guard composed of a rigid material such as hard rubber or celluloid which shall be inert to the chemical action of the poisonous preparation used or to the solution resulting from 25 the dissolving of the poisonous preparation in a liquid.

To these ends my invention consists in the novel features and parts and combinations of the same hereinafter more particularly 30 described and then specified in the claims.

In the drawings: Figure 1 is a plan view of the guard to which the poisonous preparation is molded and with which it is interlocked. Fig. 2 is a plan view of the poison-tablet. Fig. 3 is a side elevation of the same. Fig. 4 is a horizontal section of a form of mold which may be used in the manufacture of the tablet. Fig. 5 is a transverse section of a modification of the tablet. 40 Like figures of reference indicate corresponding parts in all the views.

Referring to the drawings and more particularly to Figs. 1 to 3 inclusive: 1 indicates a guard which may be of any suitable 45 shape and which is provided with an opening 2 at or near its center. The periphery or edge of the guard is serrated or provided with sharp points or prongs 3. The poisonous preparation 4, as for instance bichlorid of mercury, is molded in its plastic state 50 preferably to either face of the guard, passing through and completely filling the opening 2. The molded preparation 4 on either face of the guard may be of any suitable 55 form or shape as for instance circular as illustrated, but its circumference or area is

preferably greater than the circumference or area of the opening 2 so that the desirable feature of having the poisonous preparation interlocked with the guard is produced.

In Fig. 4 I have shown a simple form of mold adapted for use in the manufacture of my preferred form of tablet. The lower mold-plate 8 is provided with a circular opening or hole 13 having a shoulder whose 60 depth is equal to the thickness of the guard 3 and on which the guard 3 rests as illustrated. The upper mold-plate 9 is also provided with a circular opening or hole 12 adapted to register with the hole 13. The 65 plastic poisonous preparation is then poured into the mold from either side or from both sides so that the openings 12 and 13 and the opening 2 in the guard 3 are completely filled, after which the plates 10 and 11 are 70 clamped to the mold-plates and the poisonous preparation is allowed to harden. Obviously the poisonous preparation 4 is then 75 securely molded to and interlocked with the guard 3.

In the modification shown in Fig. 5, the guard 3' is provided with an opening and has a collar 15 integrally united with its edge, the upper and lower edges of the collar being serrated or provided with prongs 80 85. The poisonous preparation 4' is then molded to and interlocked with the guard 3' as in the former case, and a slightly different form of mold is used for its manufacture as 90 will be obvious.

The relatively large size of the guard and the sharp prongs or points with which it is provided make the accidental internal taking of the tablet impossible owing to the fact that the sharp prongs or points will 95 instantly prick or hurt the person attempting to swallow the tablet, and any intentional taking of the poisonous preparation would necessitate the cutting or tearing away of the same from the guard. Obviously the shape of the guard and also of the molded poisonous preparation may be varied without departing from the spirit of my invention, but it is important that the guard be composed of some hard material 100 which is inert to any undesirable chemical action of the poisonous preparation used, so that when the tablet is used by dissolving the same in water the solution resulting therefrom will not be rendered less efficacious than would be the case if the use of the guard were not employed.

It will be understood that the invention is not limited to the exact details of construction and the arrangements of parts herein shown and described, such being for the purpose of illustration only, but various modifications may be resorted to without departing from the spirit of the invention as set forth in the appended claims.

What I claim as my invention is:—

- 10 1. In a poison-tablet, the combination of a guard having a serrated edge and a poisonous preparation securely fastened to said guard.
- 15 2. In a poison-tablet, the combination of a guard having a serrated edge and provided with an opening, and a poisonous preparation molded to and interlocked with said guard.
- 20 3. In a poison-tablet, the combination of a guard having its edge provided with prongs and a poisonous preparation securely fastened to the guard, said guard consisting of a rigid substance inert to the chemical action of the poisonous preparation and to the solution resulting from the dissolving of the poisonous preparation in a liquid.
- 25 4. In a poison-tablet, the combination of a guard having a serrated edge, and a poisonous preparation molded thereto, said guard being composed of a rigid substance inert to the chemical action of the poisonous preparation and to the solution resulting from the dissolving of the poisonous preparation in a liquid.
- 30 5. In a poison-tablet, the combination of a guard with an opening therein and having its edge provided with prongs, and a poisonous preparation interlocked with said guard by molding the preparation through said opening and to the faces of said guard, said

guard consisting of a rigid material inert to the chemical action of the poisonous preparation and to the solution resulting from the dissolving of the poisonous preparation in a liquid.

6. In combination with a tablet or pellet containing poison, a guard carried by said tablet or pellet which will prevent the swallowing of said tablet or pellet, said tablet or pellet being of a size such that it might be 50 swallowed except for the action of said guard.

7. In combination with a tablet or pellet containing poison, a guard carried by said tablet or pellet and having projecting means 55 which will prevent the swallowing of said tablet or pellet, said tablet or pellet being of a size such that it might be swallowed except for the action of said guard.

8. A poisonous object and warning prongs 60 mounted on and extending therefrom, portions of the surface of said object being exposed.

9. A protector for a poisonous object comprising a body mounted upon the object, and 65 warning prongs extending from the body.

10. A poisonous antiseptic tablet and means thereon preventing the convenient swallowing of said tablet, said means being associated with said tablet to permit of the 70 ready dissolution of said tablet in a fluid regardless of said means.

Signed at New York, in the county of New York and State of New York this 27th day of December A. D. 1913.

MOSES E. BLOOM.
